TRAFFIC DETECTOR

John L. Barker, Norwalk, Conn., assignor to
 Eastern Industries, Incorporated, a corporation
 of Delaware

Application May 18, 1944, Serial No. 536,129

14 Claims. (Cl. 171—209)

1

This invention relates to an improved traffic detector, and particularly to a traffic detector utilizing the generative effect of disturbed magnetic fields, to actuate counting means, signal or warning means, traffic control systems, conveyer systems, and the like.

It is an object of the invention to provide an improved device of the magnetic type which may be disposed in or adjacent a path or channel over which vehicles, packages, or other bodies are moving, to detect such bodies as contain magnetic metal, and to employ the inductive effect of the passage thereof through a magnetic field to induce a voltage which may be employed in any desired manner in a suitable electric circuit.

It is another object of the invention to provide an improved magnetically actuated detector in which coils are disposed about relatively vertically positioned para-magnetic cores which are not pre-magnetized, but serve to direct or channel the vertical component of the earth's magnetic field.

It is a further object of the invention to provide a magnetic detector which is compensated against the disturbing effect of extraneous magnetic impulses such as created by power lines and other field-generated structures in the locality, but will be directionally sensitive to traffic flow within the relatively sharply defined field of the detector.

It is still another object of the invention to provide a traffic detector of the induced voltage generation type, which is non-critical as respects coil windings, and the type and disposition of the cores of magnetic material therefor.

It is another object of the invention to provide a traffic detector which may be permanently imbedded in the concrete or other material of a roadway, and does not require moving parts or pressure-actuated mechanisms for traffic detection.

It is another object of the invention to provide improved magnetic detection means which will differentiate between traffic moving in a plurality of directions, and will actuate detection, signalling, or control means only for traffic flowing in a predetermined direction.

It is an object of the invention to provide a magnetic traffic detector embodying spaced voltage-generation coils so arranged that the passage of magnetic material in a defined zone adjacent said coils induces voltage, of respectively reversed polarity, therein, and a novel electrical circuit for substantially nullifying the voltage generation for traffic flowing in one direction to prevent

2

operation of the traffic control or other system and thus to insure that only traffic passing in the opposite direction will be detected.

Induced voltage devices for the detection of masses of magnetic material, are known in the art, and utilize the phenomenon that a body of magnetic metal which cuts lines of magnetic force will induce a voltage in a coil disposed in the magnetic field.

The present invention contemplates the employment of a suitable plurality of bars of magnetic material—cold rolled steel bars perform satisfactorily—arranged in suitable spaced relationship in a preferably quadrilateral framewise structure, and disposed vertically, to provide channels through which pass the vertical component of lines of force of the earth's magnetism. Disposed about each said bar, is a coil of wire; a set of coils which are in the same line of position transversely of the movement of traffic are connected in parallel, and the parallel-connected coils of a set disposed therefrom in spaced relationship in the direction of traffic flow, have a reversed winding as compared with said first-named set.

Through each of the coils of each set, therefore, flow lines of force of the earth's magnetic field; and when the flux through each said coil is disturbed, as by movement of a magnetic body through the flux pattern, an E. M. F. having a characteristic voltage wave, is induced in the coils. Because of the relative reversal of winding of each set of coils, the voltage induced is of opposite polarity.

By pre-establishing the capacity value of the circuit for each set of coils so that the total capacity of one set is higher than the total capacity of the second set, the voltage effect of the first set may be delayed. Assuming that it is desired not to detect traffic flowing in such direction as to pass sequentially over the first and second coil sets, the delayed voltage may be superposed upon the voltage induced in the second coil units. By reason of the opposite-polarity characteristic of the respective induced voltages, the said voltages substantially nullify each other, and are ineffective to operate the signalling or other detection means.

Features of the invention are that the detector is accurately directionally selective over a wide range of traffic speeds and has a relatively sharply defined area of operation. An additional feature resides in its inherent compensation against extraneous field-generating influences.

In the following detailed description, the in-

vention has been illustrated with respect to its application to the detection of vehicular highway traffic, but it will be readily apparent to those skilled in the art that many other applications are within the scope of use of the invention.

In the accompanying drawings, which illustrate one practical embodiment of the invention:

Fig. 1 represents a traffic intersection, one street of which has detectors embodying the present invention; a traffic signal and a control for operating the same upon passage of vehicles across the respective detectors in the direction of the intersection, are schematically shown;

Fig. 2 is a diagrammatic representation of a detector disposed beneath the surface of the roadway, and looking in the direction of the arrows 2—2 of Fig. 1;

Fig. 3 is a plan view of apparatus embodying the present invention;

Fig. 4 is an end elevation of the same on lines 4—4 of Fig. 3;

Fig. 5 is a vertical sectional detail on lines 5—5 of Fig. 3, illustrating a coil and junction box for the electrical connections therefrom;

Fig. 6 is a wiring diagram showing the coil units and delay network;

Fig. 7 is a typical amplifier circuit; and

Fig. 8 is a diagrammatic representation of induced voltage curves, for the purpose of illustrating the objectives of superposition of induced voltages for one direction of traffic flow, and separation of voltages for traffic flow in the opposite direction.

Referring to the drawings, one practical embodiment of the magnetic detector D includes preferably rectangular frames 10, 11, joined and maintained in suitably spaced relationship, by pairs of bars or rods 12 secured thereto. Said rods serve as cores for the voltage-generator coils, arranged in sets or pairs, and designated 14, 140 and 15, 150, respectively. Rods 12 are of magnetic material; in the present invention, cold-rolled steel is substantially as effective as the high-permeability steel alloys such as Allegheny-Ludlum "4750."

For vehicular traffic control, each said frame may be 48 inches by 12 inches, and spaced 9 inches apart by the rods 12. The longer sides of each frame, which are disposed transversely of the direction of traffic flow, are preferably standard rolled steel structural shapes 16, 17 such as angle or channel iron. Each frame is completed by end pieces 18, of brass or other non-magnetic material, suitably secured as by the nuts and bolts illustrated. Brazing may be employed supplemental to, or in lieu of, the nut and bolt fastenings.

At one end of the structure, there may be supported, as by non-magnetic straps 19, a connection head 20, as later more fully described.

The rods 12 are preferably disposed symmetrically on the frame. For a 48" frame the rods may be placed 12 inches from each end of the frame, there being two rods and coil assemblies on each of the pairs of frame members 16, 17.

Each of the coils consists of a large number, for example 20,000, of turns of #40 insulated wire wound on a $\frac{1}{2}$ " core. Such a coil may be wound for housing within a non-magnetic casing 21 fixedly secured to each rod 12. The casings 21 are impervious to water or dampness; if desired, the casings may be filled with pitch, wax, or other water-repellant material.

Each coil is uniform as to its electrical char-

acteristics. The electrical values of the coils are related principally to the strength of impulse generated therein, and to local stray or leakage current conditions, as is well known to those skilled in the art. Higher voltage output is obtained by increasing the number of turns, and such output is primarily adapted to the electronic amplifier as an impulse responsive device.

The rods 12, being paramagnetic, are conductors for the vertical component of the earth's magnetic force, and the local field of the earth's magnetism passes downwardly through the coils disposed about the rods. The magnetic frame elements 16 and 17 effectively enlarge the pole areas of the rods 12 associated therewith, in that the vertical magnetic field between and at the respective sides of the coils flow along said frame elements, thence into and downwardly through the respective rods 12 for dissipation into the earth.

The respective sets of coils 14, 140 and 15, 150 are connected in parallel, as shown in Fig. 6. As is apparent from the circuit diagram, the direction of winding of one set of coils is the reverse of that of the other set, and therefore the voltage waves induced in the sets are of opposite polarity.

Leads from the respective coil sets are brought into the connection head 20, which may comprise a suitable threaded brass sleeve provided with a gland 22 through which the leads 23 pass to the control box C.

In a detector of four foot width, it has been found that it is most satisfactory to employ two coils in each of the voltage-generation units. The two coils, being connected in parallel, operate as a single generator.

Tests have established that the present detector reacts to the passage of magnetic metal in a path within six inches of either end frame member 18. The steel wheels of present day automobiles effectively induce a voltage in the coil units when passing through the magnetic field thereof, and the units are disposed in the roadway to take maximum advantage of conventional automobile tread.

For example, the unit D nearest the curb will, unless local traffic conditions dictate otherwise, be placed about six feet from the curb. Since the passage of a vehicle within six inches of the side of the unit remote from the curb is effective to generate an induced voltage, there is an effective operating area up to about five and one-half feet beyond the four foot width of the unit itself. Accordingly, one unit is effective over a fifteen foot traffic lane. For wider lanes, a plurality of units D may be connected in series addition.

The units are installed in the roadway by excavating a suitable depression, temporarily supporting the unit therein, and completely filling the excavation with the road material. The units are not critical, and need not be accurately leveled, as must units in which the magnetic field is essentially transverse, rather than vertical.

It is, of course, recognized that an automobile body—in fact any metallic structure—is not magnetically homogeneous and the thereby induced wave form is not uniform or regular. A resultant action is present in each vehicle regardless of its heterogeneous magnetic condition. Therefore, the effect of the vehicle on two similar detector coils, will be similar.

For simplicity of demonstration of the induced voltage curves of the respective sets of coils, Fig. 8 shows a theoretical voltage curve obtained by

the passage of a theoretically homogeneous magnetic structure successively over the sets of coils. Assuming movement of the imaginary magnetically homogeneous body initially across coils 14, 140, the voltage induced in said coils builds up as it approaches the effective axis of the coils, attaining a maximum value in plus direction immediately in advance of passing over said axis, then sharply declining to zero at the instant of passing, and building up to an equal negative value before again tapering off to zero as the magnetic body recedes.

Substantially the same voltage curve derives as the body approaches, passes over, and recedes from the coils 15, 150; however, the reverse winding of said coils results in reversed polarity.

The reversed windings, and resultant reversed polarity of the induced voltages, operate as compensating means to preclude operations of the traffic control system by the magnetic field effect of such structures as overhead trolley or power lines, subsoil conductors or the like, which usually parallel the roadway, and hence extend across the detector and simultaneously subject each coil unit thereof to a magnetic field.

To produce apparatus which is directionally selective over a wide range of vehicle speeds, and resultant range of frequencies of the induced current, I include in the circuit, see Fig. 6, an electrical network which will introduce a substantially uniform space delay at all frequencies. The network increases the total capacity of the coil unit which is first to receive the impulse from traffic moving in the direction which is not to be detected. The network delays the induced voltage after the passage of the vehicle over the coil unit, and substantially superposes the said voltage on the approximately equal but oppositely polar voltage subsequently induced in the second coil unit, for traffic moving and the direction of the "TRAFFIC DIRECTION" arrow as shown in Fig. 8. Hence, there is a substantial cancellation of voltage and resultant non-operation of the control or other apparatus in the circuit with the detector for traffic moving in such direction.

Assuming traffic in the opposite direction (i. e., opposite to the "TRAFFIC DIRECTION" arrow in Fig. 8), the delay network distinguishes rather than superposes, the induced voltages, and either or both of the voltages generated may be employed to actuate the control or other apparatus.

The respective sets of coils 14, 140 and 15, 150 are interconnected in a three-wire circuit, including conductors 30, 31 and 32, the latter being common to the respective coils and the delay network, see Fig. 6. Condensers 33, 34 preload the circuit to compensate for possible variations in cable length, and resistances 35, 36 introduce a resistance preload in the respective circuits. Said resistances are conveniently of 4000 ohms each. Resistances 37, 38 of 400 ohms each serve in combination with the resistances 40, 42 and 41, 43, respectively, as voltage divider means. Typical values are 10 and 500 ohms respectively for resistances 40 and 42, and 100 and 5000 ohms, respectively, for resistances 41 and 43.

A condenser 44, of large capacity, say 40 mfd., is in series with resistor 40, and is opposed by condenser 45 of 8 mfd., in series with resistor 41. Similarly, condenser 46, of 8 mfd. is across leg 30, 32, and condenser 47, of .1 mfd., is across leg 32, 31.

It will be understood that the stated values of the respective electrical elements are subject to change in the field. Local conditions affect the

voltage generation, circuit capacity, etc., and may not accurately be foretold.

As is apparent, the respective circuits 30, 32 and 31, 32 are unbalanced, and the former has substantially greater capacitance. Voltage generated in the former circuit will therefore be delayed as respects generation in the latter; and the result of the unbalanced capacitance is to superpose the respective induced voltages as aforesaid. The extent of unbalance, however, is not so great as to result in widely variant voltage output of the respective coil sets.

Condenser 44, being of relatively large capacity, is primarily effective for low traffic speeds, such as not in excess of 25 M. P. H., whereas at higher speeds, it is desirable to have a greater ratio between the opposed condensers in the respective legs, as evidenced by the relationship of 8 mfd. in condenser 46, as opposed to .1 mfd. in condenser 47.

Experimental tests over a wide range of vehicular speeds indicate that the combination of the condensers 44, 46, in opposition to condensers 45, 47, affords a correct "space delay" whereby at any speeds from 3 M. P. H. to 60 M. P. H., the induced voltages are superposed for traffic passing initially over the coils 14, 140.

A typical amplifier circuit is shown in Fig. 7, it being understood that multi-stage amplification may be employed if necessary or desirable.

The impulse from conductors 30, 31 is impressed across the grid of tube 50. For traffic passing in a direction which is not to be detected, the small impulse from said conductors, by reason of the substantial nullification of the induced voltages, is insufficient to reduce the negative grid bias normally supplied from source 51, and there is insufficient output from the tube 50 to energize and operate circuit closing relay 52, the output leads of which serve the traffic control S or other associated apparatus.

For vehicles passing in the opposite direction, however, there are two distinct voltages impressed on the negative grid bias, and the positive components of such induced voltages reduce the negative grid bias, to increase the plate current of the tube 50, and hence actuate the relay to close the output circuit thereof.

Galvanometer relays, or other relays of a polarized type may be employed in lieu of the illustrated amplifier and relay. However, the sturdier construction and dependability of the thermionic amplifier makes it generally more satisfactory over long periods of operation.

Whereas it is obvious that among the several objects of the invention as specifically aforesaid are achieved, it is apparent that numerous changes in construction and rearrangements of the parts might be resorted to without departing from the spirit of the invention as defined by the claims.

I claim:

1. In a direction selective traffic detection apparatus having an electric output device to be actuated only by bodies containing magnetic material passing in a selected one of two permissible directions of traffic along a traffic artery, the combination of two voltage-generation coils having magnetic fields passing therethrough, said coils being spaced sequentially along said artery in the path of traffic flow, whereupon the passage of said magnetic bodies sequentially through the field of each coil induces a voltage therein, an electric circuit interconnecting said coils in series opposition for reversing the polarity of voltage

generation in one coil with respect to the other, an output circuit from said coils, a work circuit connected to the respective output circuits of said coils for transmitting generated voltage to said output device; and a delay network including a plurality of capacitors of successively less capacitance individually connected across the output circuit of each of said coils, the capacitors of one said output circuit being respectively less than the correspondingly positioned capacitors of the other of said output circuits, whereby the voltage generation in the coil having the higher capacitance is delayed for substantial coincidence with the subsequently generated and oppositely polar voltage induced in the other coil for traffic flowing in one direction to result in substantially zero voltage in the work circuit and the successively generated voltages are individually apparent in the work circuit for traffic flowing in the opposite direction.

2. In a direction selective traffic detection apparatus having an electric output device to be actuated only by bodies containing magnetic material passing in a selected one of two permissible directions of traffic along a traffic artery, the combination of two voltage-generation coils spaced sequentially along said artery in the path of traffic flow, means for passing a magnetic field through said coils, whereupon the passage of said magnetic material sequentially through the field of each coil induces a voltage therein, conducting means interconnecting said coils in series opposition for reversing the polarity of voltage generation in one coil with respect to the other, an output circuit from said coils; a work circuit connected to the respective output circuits for transmitting the voltage generated by said coils to said output device; and a delay network including a relatively high-value capacitor across the output circuit of one of said coils, and a lesser-value capacitor across the output circuit of the other of said coils, whereby the voltage generation in the coil having the higher capacitance is delayed for substantial coincidence with the subsequently generated and oppositely polar voltage induced in the other coil for traffic flowing in one direction to effect substantially zero net voltage in said work circuit and is separate therefrom and is thereby apparent as individual voltage pulses in the work circuit for traffic flowing in the opposite direction.

3. In a traffic detector of the magnetic type adapted to be located adjacent to a path of traffic flow and including voltage actuated means for directionally detecting the passage of magnetic units of traffic in such path, the combination of two voltage-generation coils spaced sequentially along said path, paramagnetic cores in each of said coils for directing the vertical component of the earth's magnetic field therethrough, whereupon the passage of magnetic material through the field of each said coil induces a voltage therein, conducting means interconnecting said coils in series opposition for the generation in each coil of a voltage of opposite polarity, an output circuit from said coils, a work circuit connected to the respective output circuits of the coils for transmitting generated voltage to said voltage actuated means; and an electrical network in circuit with at least one of said coils and embodying capacitors to delay the voltage generation thereof for substantial coincidence with the voltage generated in the second of said coils for traffic flowing in one direction to substantially nullify the respectively generated

voltages, and to distinguish the respectively generated voltages for traffic flowing in the opposite direction whereby said voltage actuated means will not be operated upon traffic flow in the said one direction.

4. A device for the detection of magnetic bodies traversing a predetermined traffic path, comprising voltage generator means including cores of magnetic material disposed in spaced relationship along the path of traffic flow and a coil of wire disposed about each said core, whereby passage of magnetic metal sequentially through the fields of the respective generator means induces distinct voltages therein; conductor means interconnecting said coils in series opposition, and affording a conductor from each coil for external connection; an electrical network in circuit with said conductors and including means whereby the capacity of the output circuit of one of said voltage generating means is greater than that of the second of said voltage generating means to delay the voltage generation in the first-named generator for substantial superposition upon the voltage generation of the second said generator to substantially nullify the output of the respective generators for traffic flow sequentially across the generators in one direction and to distinguish the voltages upon traffic flow in the opposite direction.

5. A device for the detection of magnetic bodies traversing a predetermined traffic path, comprising electromagnetic generators including a magnetically permeable core and coil unit disposed in spaced relationship along said traffic path and arranged for induced-voltage generation in each said electromagnetic means upon passage of a magnetic body successively within the magnetic field of each said generator; an electric circuit interconnecting said generators in series opposition, whereby the voltage generated in each said means is of reversed polarity; combined capacitance and resistance means in circuit with one of said generators to delay the voltage generation therein, whereby to impose the said voltage upon the reversed-polarity voltage of the second of said generators for traffic flowing in one direction and to distinguish the respectively generated voltages for traffic flow in another direction.

6. A device for the detection of magnetic bodies traversing a traffic path, comprising an organization of paramagnetic cores disposed vertically and in spaced relationship in line transversely to flow of traffic; a voltage-generation coil about each of said cores, said coils being interconnected in parallel; a second organization of paramagnetic cores and parallel connected coils thereon disposed vertically and in spaced relationship transversely of traffic flow, said two organizations being mutually spaced in the direction of traffic flow; means for connecting the respective coil organizations in series opposition and affording output conductors for the respective organizations from such series opposition connection.

7. In a direction-responsive traffic detector the combination of a coil of wire disposed beneath the path of traffic flow; a second, similarly disposed coil of wire spaced from the first coil in the direction of traffic flow; a paramagnetic core within each said coil and extending vertically with respect to said traffic path to conduct lines of force of the earth's magnetism through the said coils, whereby passage of magnetic metal above said coils induces a voltage

therein; means for reversing the polarity of the said induced voltage of one coil with respect to the other; and means for delaying the generation of voltage in one coil proportionally to the speed of passage of said magnetic metal to superpose the respectively induced voltages for traffic flowing in one direction and for separating the said voltages for traffic flow in the opposite direction.

8. A compensated traffic detector apparatus, comprising a pair of substantially identical detecting elements each comprising a magnetically permeable core and a coil thereon, said cores being disposed substantially vertically for subjecting to the vertical component of the earth's magnetic field and arranged in spaced relationship in the direction of traffic flow in a traffic path, conductors interconnecting the coils of said detecting elements in series in electrically opposing relationship with respect to voltages induced therein by variations in the magnetic field within each said coil and providing output leads from such series connection.

9. A voltage-generation unit for a traffic detection device, comprising relatively long, rigid members of magnetic material arranged transversely to a traffic path, relatively short spacers of magnetic material for disposing the said members in vertically spaced relationship beneath such traffic path and said spacers being themselves spaced transversely to such path, and coil means disposed about each of said spacers and electrically interconnected in parallel.

10. A voltage-generation unit for a traffic detection device, including an elongate frame having structures of magnetic material extending transversely of the path of traffic flow and maintained in fixed spaced relationship in the direction of traffic flow by non-magnetic means; a paramagnetic core extending substantially vertically from each of said magnetic structures, and a coil of wire disposed about each of said cores, the windings of the respective coils being connected in series opposition relatively to each other.

11. A voltage generation unit for a traffic detection device, comprising a relatively long, rigid structure of magnetic material disposed transversely of the path of traffic flow; spaced paramagnetic core means secured to said structure and extending substantially vertically downwardly therefrom; and coil means disposed about each said core means and electrically interconnected in parallel.

12. A voltage-generation unit for a traffic detection device, adapted to be disposed across a traffic path, comprising relatively long rigid members of magnetic material, spacers of magnetic material for disposing the said members in vertically spaced substantially parallel relationship and said spacers being relatively short compared to said members and being spaced in substantially parallel relationship, along said members and substantially perpendicular thereto and coil means disposed about each of said spacers and electrically interconnected in parallel.

13. A voltage-generation unit for a traffic detection device adapted to be disposed across a

traffic path, comprising a framework of relatively long rigid members of magnetic material adapted to be disposed transversely to a traffic path and spacers of magnetic material disposing the said members in vertically spaced substantially horizontal planes and said spacers being relatively short compared to said members and being spaced along said members in substantially perpendicular relation to such planes, and coil means disposed about each of said spacers and electrically connected in parallel for generation of voltage in such coil means upon passage of traffic containing magnetic material across said framework, another framework and associated coil means similar to the first mentioned framework and coil means, means of substantially non-magnetic material spacing the two frameworks in substantially parallel vertical planes; and means connecting the coil group of one framework in series opposition with the coil group of the other framework.

14. A traffic detector device including a framework of relatively long rigid members of magnetic material adapted to be disposed transversely to a traffic path and spacers of magnetic material disposing the said members in vertically spaced substantially horizontal planes and said spacers being relatively short compared to said members and being spaced along said members in substantially perpendicular relation to such planes, and coil means disposed about each of said spacers and electrically connected in parallel for generation of voltage in such coil means upon passage of traffic containing magnetic material across said framework, another framework and associated coil means similar to the first mentioned framework and coil means, means of substantially non-magnetic material spacing the two frameworks in substantially parallel vertical planes; and means connecting the coil group of one framework in series opposition with the coil group of the other framework, and means delaying generation of voltage in the coil group of one framework for substantial superposition and neutralization of voltages for traffic in one direction and for separation of voltages for detection of traffic in the opposite direction.
